UNITED STATES PATENT OFFICE.

EUGENE CARPENTER, OF NEWTON, MASSACHUSETTS.

SHOW-CASE.

1,094,120.

Specification of Letters Patent. Patented Apr. 21, 1914.

Application filed June 18, 1912. Serial No. 704,315.

To all whom it may concern:

Be it known that I, EUGENE CARPENTER, a citizen of the United States, residing in Newton, in the county of Middlesex and 5 State of Massachusetts, have invented an Improvement in Show-Cases, of which the following description, in connection with the accompanying drawings, is a specification, like letters on the drawings representing 10 like parts.

The present invention relates to a refrigerated show case, and is embodied in a case of novel construction and arrangement in which the front and top are of glass, 15 while the base and the rear wall are of insulated material, the rear wall having a shelf projecting forward a short distance for convenience of the salesman in handling goods, making out sales slips, &c.

20 The rear portion of the upper part of the show case is arranged to slant, and is provided with sliding covers, which may be made of plate glass, and which are arranged to overlap and slide in opposite directions, so that any part of the case can be 25 opened for the removal of the goods therein. The base and rear of the case may be made of any suitable material, preferably wood, each of the said portions being made in two 30 parts with insulating material interposed, the rear wall being provided with a shelf below which the refrigerating pipes, which keep the interior of the case cool, may be supported.

35 At the front of the base, the case is provided with two or more brackets or supports preferably made of metal, these brackets extending vertically upward to support the front wall of the case, and then horizontally 40 rearward to support the top; and from the back of the top the brackets are inclined downward to a point where they are connected with the front of the shelf at the rear of the case.

45 The vertical and horizontal portions of the brackets afford supports for the glass front and top of the case, while those portions of the bracket which incline downward and rearward to the shelf are provided with guide-ways at the rear of the horizontal portion to receive the sliding covers, the opposite edges of which covers rest in similar guide-ways formed in the shelf at the rear.

55 Figure 1 is a perspective view, partly in

section, of a show case embodying the invention; Fig. 2 is a vertical section of the same on a somewhat larger scale; and Fig. 3 is a rear view of the middle portion of the case with the ends broken away, and parts 60 shown in section.

The case embodying the invention is provided with the base *a* and rear wall *b*, these parts each being shown as casings of suitable material, preferably wood, containing 65 insulating material *c* between the two parts of each casing. At the top of the rear wall *b* is a shelf *d* projecting forward a short distance, this shelf being below the top of the show case and forming a convenient 70 shelf for the use of the salesman, and also a cover to inclose a series of refrigerating pipes *e* at the back of the case.

The transparent portion of the case, which is preferably of plate glass, is supported 75 by means of brackets *f*, the vertical portions of said brackets affording a backing for the glass front *g* of the case, each bracket having a horizontal portion *f*², and an inclined portion *f*³ extending rearward from said horizontal portion to the front of the shelf *d*. The horizontal portions *f*² afford supports 80 for the stationary glass cover *g*² at the front of the show case, while the sliding covers *g*³ and *g*⁴ overlie the inclined portions *f*³ of 85 the brackets and extend from the top *g*² to the shelf *d*.

In the construction shown, the covers *g*³ and *g*⁴ overlap at adjacent ends, the lower cover being narrower than the upper, and 90 the two covers sliding in separate guideways one above the other, being held entirely by gravity so that they can be lifted out at any time, if it is desired to leave the case open. In the construction shown, these covers are 95 made of plate glass, but it is obvious that any suitable material may be used, whether transparent or opaque, without departing from the invention.

The shelf *d* is shown as provided with 100 guide shoulders *d*² and *d*³ for the covers *g*³ and *g*⁴, respectively, each shoulder being formed at the bottom of the vertical abutment which affords a lateral guide for the sliding cover. The opposite sides of the 105 covers are supported upon similar shoulders *h*² and *h*³ formed in a guide strip *h* which is secured to the brackets *f* between the horizontal portions *f*² and the inclined portions *f*³.

In the construction shown, Fig. 2, the brackets are in the form of castings, T-shaped in cross section, and the guide member h is secured to the vertical face of the 5 T-shaped casting where the said casting is curved at the joint between the horizontal and inclined portions; screws f^4 , or similar fastening devices, being sufficient to hold the guide strip in place.

10 The case constructed as above described is perfectly inclosed, and at the same time accessible, while all the parts can readily be kept clean, the construction at the same time being durable and not expensive.

15 What I claim is:

1. A show case comprising a base and a rear wall, combined with brackets secured to the front of the base and having vertical, horizontal, and inclined members; transparent vertical and horizontal closing walls supported by said brackets; a horizontal closing wall extending forward from the rear wall of the case, to which the inclined members

of the brackets are fastened; and covers supported over said inclined members. 25

2. A show case comprising a base and a rear wall, combined with brackets secured to the front of the base and having vertical, horizontal, and inclined members; transparent vertical and horizontal closing walls supported by said brackets; a horizontal closing wall extending forward from the rear wall of the case, to which the inclined members of the brackets are fastened, said horizontal wall having guideways in different planes; 30 a guide strip supported on the upper part of the inclined members and having similar guideways in different planes, and overlapping covers supported in said guideways.

In testimony whereof, I have signed my 40 name to this specification in the presence of two subscribing witnesses.

EUGENE CARPENTER.
